UNITED STATES PATENT OFFICE.

ISAAC W. P. BUCHANAN, OF LEBANON, TENNESSEE.

VARIABLE SPRAY DEVICE.

Application filed February 11, 1925. Serial No. 8,561.

This invention relates to hand operated continuous variable spray devices, the general object of the invention being to so construct the device that it can be sold at low cost and operated by persons of no or little mechanical knowledge with but little danger of its getting out of order.

Another object of the invention is to provide a cap for the liquid container of the device, having a chambered head or dome with which communicates an eduction tube having an adjustable nozzle and stabilizing means therefor on its outer end and through which passes a liquid tube which also extends into the liquid in the container, with a hand pump for introducing air into the head so that some of the air will pass downwardly into the container and place the liquid therein under compression to force the liquid through the liquid tube, and some of the air will pass directly into the eduction tube and act on the liquid emerging from the liquid tube and thus cause the liquid to pass from the nozzle in the form of a spray, the adjustable nozzle acting as means for controlling the texture of the spray.

Another object of the invention is to so position the liquid tube in relation to the eduction tube that the delivery end portion of the liquid tube is circumferentially spaced from the delivery end portion of the eduction tube to form an annular unobstructed air outlet passage. This passage serves two purposes, one being that the emerging liquid is contacted on all sides by the air under pressure, thus producing a uniformly textured spray and the other being that this annular passage is not as likely to be clogged as a more restricted passage, and if clogged, it is more easily cleaned.

A further object of the invention is to provide means for rigidly holding the liquid tube against movement in the eduction tube so that the nozzle can be adjusted from a position where it rests against the end of the liquid tube to varying distances from said end without danger of movement of the liquid tube interfering with the functioning of the nozzle in producing a variable spray.

To the attainment of the foregoing, the invention consists in the improvement as

hereinafter described and definitely claimed.

In the accompanying drawings, forming part of this specification:—

Figure 1 is a fragmentary view of the improved device, with parts in section and parts in elevation.

Figure 2 is a section on line 2—2 of Figure 1.

Figure 3 is an enlarged sectional view through the nozzle part of the device.

Figure 4 is an elevation with parts in section, showing a modification of the nozzle part.

Figure 5 is an elevation with parts in section, of another modification.

Among other elements, my novel device comprises a tank 1. The said tank 1 is provided with a neck 2 threaded at 3 and terminating at its upper end in an inwardly directed annular flange 4.

The device also comprises a cap member 9 for use on the neck 2. Said cap member 9 is threaded as shown to engage the thread 3 of the neck 2 and is formed at its upper end with a hollow head or dome member 12, the chamber formed by said hollow head or dome member being designated by 13, and said head is provided at its upper end with a threaded projection 14. A gasket is placed 80 between the cap and flange 4.

At diametrically opposite points, the hollow head 12 is provided with threaded apertures 20 and 21. The aperture 20 is for the reception and connection of a forward tubular extension 22 on a combined handle and pump cylinder 23, said cylinder 23 containing a reciprocating piston (not shown) in connection with a handle disposed in rear of the cylinder, as usual. In the tubular extension 22 is a forwardly opening non-return valve 26. The threaded aperture 21 is for the reception and engagement of an eduction tube 30, the said tube 30 receiving the smaller liquid tube 31 which has a portion extending 90 down into the tank 1.

As will be seen, the liquid tube is open at both ends with one end protruding from the liquid tube and that part of the liquid tube in the eduction tube is centrally arranged 100 with relation to the eduction tube so as to provide an annular air passage, the liquid

- tube being supported in any suitable manner, such for instance by forming indentations in the eduction tube to engage the liquid tube, as shown in Figure 4, with the bent part of 5 the liquid tube being held between the inner end of the eduction tube and a part of the wall of the hollow head. Thus the liquid tube is held in fixed relation to the eduction tube.
- 10 I prefer to employ a fine wire screen 33 at the lower end of the chamber 13 in the hollow head 12 to preclude the possibility of any fire being drawn rearwardly in the tube 30 or being allowed to gain access to 15 the interior of the tank 1 incident to the reciprocations of the piston in cylinder 23, when the device is used as a flame thrower, as it may be by spraying kerosene oil and igniting the same by a match 30^x held in a 20 clamp 30^w which may be attached to the eduction tube 30, as shown, the principle being the same as that in the Davy mine lamp. This screen also acts to prevent the contents of the tank 1 from entering the 25 dome member 12 if the tank should be upset, as this screen is of such a fine mesh as to practically prevent any liquid passing through the same. This will prevent the contents of the tank from clogging the 30 spraying parts.
- The forward portion of the eduction tube 30 is exteriorly threaded as shown for the engagement of a threaded nozzle 40 and a threaded lock nut 41, the lock nut 41 being 35 located in rear of the nozzle 40, and the two being separated by a washer 43 whereby when the nozzle 40 is positioned on the tube 30 and the nut 41 is turned to jamb the washer 43 against the nozzle, casual movement 40 of the nozzle with respect to the tube 30 will be precluded and undue loss of compressed air prevented. As shown, a nozzle 40^a with a larger eduction orifice than that of the nozzle 40 is provided for use interchangeably with the nozzle 40, the nozzle 45 that is not in use being detachably secured on the projection 14 of the hollow head or dome member 12. The aperture in each tip must be smaller than the opening in the liquid tube so as to cause a varying back pressure of the air from the eduction tube on the liquid emerging from the liquid tube. As shown in Figure 3, the lock nut is chambered at 60, to receive a part of the 50 washer 43.
- 55 It will be manifest from the foregoing that when the nozzle on the eduction tube 30 is adjusted relative to the liquid tube 31, the device may be adapted to throw a coarse or long spray, even a solid stream or a short and fine spray, the first-named stream or spray being brought about by positioning the nozzle with its orifice close to the eduction end of the liquid tube 31, and 60 the latter spray being brought about by
- positioning the eduction orifice of the nozzle at a greater distance from the eduction end of the liquid tube 31. For instance, when the tip or nozzle is in contact with the end of the liquid tube, the air from the air passage cannot contact the stream of liquid passing from the liquid tube so that a solid stream of liquid passes from the device, but when the tip or nozzle is removed slightly from contact with the end of the liquid tube, permitting air to act on the liquid, the pressure of this air on the emerging liquid is slight, due to friction of passage of compressed air through the small annular opening, thus allowing large quantities of liquid to emerge under low pressure of small quantities of air, thereby producing a coarse texture atomization. When the tip is moved farther from the end of the liquid tube, more compressed air contacts 75 with the stream of liquid, thus acting to hold back more liquid and subjecting the smaller amount of emerging liquid to a greater pressure, thereby causing a correspondingly finer textured atomization. 80
- Attention is called to the fact that the annular air passage formed by spacing the delivery end portion of the liquid tube circumferentially from the delivery end portion of the eduction tube, causes the compressed air discharging from the eduction tube to contact the liquid emerging from the liquid tube with equal pressure on all the sides, thus producing a spray of uniform density and texture. This annular passage is not 85 likely to be clogged as a more restricted passage would be, and if clogged, it is more easily cleaned. Either nozzle 40 or 40^a may be employed, according to the use to which the device is to be placed. 90
- I have found that it is absolutely necessary to provide a lock nut and washer or their equivalents to hold the tip or nozzle in adjusted position and to prevent leakage of liquid and air at the rear of the nozzle, as I found without such means, the nozzle would quickly get out of adjustment due to the ordinary handling of the device and that air and liquid would escape from between the nozzle and the eduction tube. It 95 is extremely important to hold the nozzle in adjusted position, particularly when the device is used for painting, for the slightest movement of the nozzle will vary the quantity and texture of the spray and thus give 100 the painted object an uneven coating. The loss of air through leakage necessitates the pump being actuated at a greater speed so that the operator soon tires and the leakage of liquid results in a flame at the rear 105 of the nozzle, when the device is used as a flame maker, which seriously detracts from the efficiency of the device and when the device is used for painting, the liquid paint 110 dripping from the nozzle will fall upon 115
- 120
- 125
- 130

the surface being painted and thus cause spots. Thus it will be seen that the lock nut and washer serve three distinct purposes, each of which is absolutely essential to the proper and efficient functioning of the spray device.

It will be manifest from the foregoing that through the medium of my novel device, which obviously can be handled with great facility, a liquid spray may be produced, or a flaming spray may be produced by igniting the liquid coming from the nozzle by a match 30^x held in the holder 30^w. In fact, through the medium of my novel device, a variable straight-away liquid spray from one to eight feet in length may be produced and used for the customary purposes; also, a variable flaming spray from six inches to four feet in length may be produced, the liquid in the tank 1 being in such case an appropriate hydrocarbon and the result being a simultaneous chemical and heat sterilization. In this use, if an object to be sterilized is arranged between the extremities of the flaming spray, the said object will be subjected to the action of a direct heat sterilization and a boiling hot chemical sterilization. Again it will be appreciated that my novel device affords an instantaneous blow torch and general utility flame, and this without danger as gasification takes place exteriorly of the device and the flame does not come in contact with the nozzle. In this connection, I would have it understood that a long flame the intensity of which is lessened in proportion to its length, is best for the removal of paint inasmuch as it is not liable to scorch wood.

It will further be appreciated from the foregoing that my novel device is susceptible of being used to advantage for a multiplicity of purposes such as starting fires, soldering and unsoldering connections, thawing frozen pipes, spraying paint, heating the intake manifolds of automobile internal combustion engines, etc., and for the customary spraying of liquids.

The device is also especially useful for spraying liquid paints of the lacquer type which dry so quickly that it is practically impossible to apply them with a brush.

In the various uses to which my novel device is put the combined handle and cylinder 23 is held in the left hand and the handle 55 of the piston is actuated by the right hand, the discharge from the nozzle being accurately directed to the point of use without difficulty on the part of the user.

I prefer to employ for the production of a variable liquid spray the means best shown in Figure 3, but I would have it understood that when desired, the lock nut itself may be of heavy leather, in which event the interposed washer would be altogether omitted.

It will also be noted that in the embodi-

ment shown in Figure 1, the liquid tube 31 is fixed by being forced against the back wall of the dome chamber 13, as the eduction tube 30 is screwed in the dome, no soldering whatever being resorted to.

The embodiment of the invention shown in Figure 4 is characterized by a sleeved atomizing tip 40^e, the sleeve of which is under pressure by virtue of a stuffing box 41^e on the eduction or air tube 30^e, and is adjustable lengthwise of said tube and adjustably held in position by the frictional contact afforded by said stuffing box.

The modification of Figure 5 includes an atomizing tip 40^f subjected to pressure and held against casual turning on the eduction tube 30^f by a coil spring 31^f on the said tube, said spring bearing directly against a metallic washer 32^f, separated from the tip by a leather washer 33^f.

I have explicitly described the illustrated and preferred embodiments of my invention in order to impart an exact understanding of said embodiments. I do not desire, however, to be understood as confining myself to the specific construction of the illustrated embodiments inasmuch as the scope of my invention is defined by my appended claims, and various changes may be made within the claims without involving departure from my invention.

I claim:—

1. A continuous variable hand operated spraying device, comprising a container, a hollow head thereon and communicating therewith, a hand operated air compressing pump rigidly connected with the head for introducing compressed air into the head and container and for manipulating the spraying device when in use, an eduction tube having one end connected to and in communication with the hollow head, a liquid tube open at both ends extending through the eduction tube with its outer end protruding from the eduction tube and having its inner end portion depending into the container, the delivery end portion of said liquid tube being circumferentially spaced from the delivery end portion of the eduction tube to form an annular unobstructed air outlet passage, means for immovably fixing the liquid tube relative to the eduction tube, thereby holding its protruding end in fixed relation to the outer end of the eduction tube, an atomizing tip 120 adjustably mounted on the outer end of the eduction tube so that it can be moved into sealing engagement with the outer end of the liquid tube or held in spaced relation thereto, thereby wholly or partially preventing compressed air from the eduction tube from contacting the emerging liquid, and the aperture in the tip being smaller than the outlet from the liquid tube, thereby 125 causing, with the adjustment of said tip, a 130

- varying back pressure on the emerging liquid, and means for stabilizing the atomizing tip in its successive positions on the eduction tube and preventing the escape of air and liquid except through said aperture.
2. A continuous variable hand operated spraying device, comprising a container, a hollow head thereon and communicating therewith, a hand operated air compressing pump rigidly connected with the head for introducing compressed air into the head and container and for manipulating the spraying device when in use, an eduction tube having one end threadedly connected into the head and in communication with the hollow head, a liquid tube open at both ends extending through the eduction tube with its outer end protruding from the eduction tube and having its inner end portion depending into the container, the delivery end portion of said liquid tube being circumferentially spaced from the delivery end portion of the eduction tube to form an annular unobstructed air outlet passage, said

threaded end of the eduction tube comprising adjustable means for immovably clamping the liquid tube against a portion of the head, thereby holding its protruding end in fixed relation to the outer end of the eduction tube, an atomizing tip adjustably mounted on the outer end of the eduction tube so that it can be moved into sealing engagement with the outer end of the liquid tube or held in spaced relation thereto, thereby wholly or partially preventing compressed air from the eduction tube from contacting the emerging liquid, and the aperture in the tip being smaller than the outlet from the liquid tube, thereby causing, with the adjustment of said tip, a varying back pressure on the emerging liquid, and means for stabilizing the atomizing tip in its successive positions on the eduction tube and preventing the escape of air and liquid except through said aperture.

In testimony whereof I affix my signature.

ISAAC W. P. BUCHANAN.
